Inventor

By His Attorney

UNITED STATES PATENT OFFICE.

JOHN GEORGE, OF PARSONS, PENNSYLVANIA.

PACKING-BOX.

SPECIFICATION forming part of Letters Patent No. 429,517, dated June 3, 1890.

Application filed April 12, 1890. Serial No. 347,622. (No model.)

To all whom it may concern:

Be it known that I, JOHN GEORGE, a citizen of the United States of America, residing at Parsons, in the county of Luzerne and State 5 of Pennsylvania, have invented certain new and useful Improvements in Packing-Boxes; and I do hereby declare the following to be a full, clear, and exact description of the invention, such as will enable others skilled in the 10 art to which it appertains to make and use the same, reference being had to the accompanying drawings, and to letters of reference marked thereon, which form a part of this specification.

15 My invention relates to certain new and useful improvements in packing-boxes for lamp-chimneys; and it consists of an outer casing or box provided at its bottom with ledges, upon which the lower tray rests, and 20 with upper ledges, which bear upon the upper edges of the upper tray, said packing-box being intended for use with three trays arranged in vertical series, the upper and lower trays having central cross-pieces attached to 25 the frames and horizontal partitions of rubber, the bottom section also being provided with a perforated horizontal partition of rubber, combined with a central section consisting of a frame having large perforations, in 30 which the bases of the lamp-chimneys are adapted to rest, the parts being combined to hold lamp-chimneys securely in place when the lid of the box is closed, as will be herein-after fully set forth, and particularly pointed 35 out in the claim.

In the accompanying drawings, Figure 1 is a perspective view of a box, the cover being shown raised and the two sides thereof left off to better illustrate the construction. Fig. 40 2 is a transverse section showing the lamp-chimneys in place.

A refers to the side of the box, to which the bottom A' is rigidly secured, and this bottom is provided, adjacent to the sides A A, with 45 strips a, and to the top of the box is secured a hinged cover B, having strips b rigidly secured thereto.

C refers to the lower section of the packing case or tray, which is made up of a frame having a central transverse strip c, and to the upper and lower edges of the frame and strip are

firmly secured partition-plates c' and c'', which are preferably made up of rubber cloth. The lower section is secured to the central partition-strip, and the upper section is provided with perforations c'', which are of substantially the same size as the upper portion of the chimney, which enters said perforations when the packing-case is in use. The lower edges of the outer frame, which are 55 covered by the rubber fabric, rest directly upon the upper edge of the strips a, secured to the box.

D refers to the central section or partition, which consists of an outer frame, to the upper edges of which is secured a rubber fabric d, having perforations d', which are of larger diameter than the perforations c'' in the fabric. The upper section E is also made up of an outer frame; but it has a transverse 70 partition e, and to the upper edge of the same is secured an imperforated sheet of rubber fabric e'. An eye is also provided for removing this upper section; and it is of such a height that when the hinged cover of the box 75 is lowered the strips b, which are attached thereto, will contact therewith.

In packing lamp-chimneys in my improved carrier they are placed as shown in the accompanying drawings, the tops of the chimneys being placed downwardly, so that they will rest upon the imperforated sheet of fabric c'', while the opposite end bears upon the fabric e'. In order to remove the chimneys, it is only necessary to remove the upper section E, which can be done by grasping the eye with which the upper section is provided. By extending the strips entirely across the frames the projecting edges will serve as a packing, so that when the sections are pressed 85 upon each other they will be immovable.

I am aware that prior to my invention it has been proposed to provide packing-boxes for lamp-chimneys with an outer casing, to which conical sections are attached, which 95 are adapted to fit in the upper and lower ends of the lamp-chimneys, while said packing-box has intermediate perforated plates, and I do not claim such construction, broadly; but

What I claim as new, and desire to secure 100 by Letters Patent, is—

In a packing-box for lamp-chimneys, the

combination of an outer casing having a hinged cover and interior strips *a* and *b*, a series of frames, the upper and lower frames having transverse partitions and imperforated 5 horizontal partitions of rubber fabric, the lower section having a perforated horizontal partition, a central section consisting of a side frame and perforated partition, the parts being organized so that the frames will rest

one upon the other, the horizontal partitions serving as interposed packing, substantially as shown, and for the purpose set forth.

In testimony whereof I affix my signature in presence of two witnesses.

JOHN GEORGE.
